CLAIM

I claim the novel design for a USB universal docking station, as shown and described.

DESCRIPTION

FIG. 1 a top, front right-side perspective of my new design for a USB universal docking station,

FIG. 2 a left-side elevation thereof,

FIG. 3 a right-side elevation thereof,

FIG. 4 a front elevation thereof,

FIG. 5 a rear elevation thereof,

FIG. 6 a top plan view thereof; and,

FIG. 7 a bottom plan view thereof.

The broken lines in the drawings depict parts of the USB universal docking station that form no part of the claimed design.
